David Hathaway, of Troy, New York.

Assignor to

Fuller, Warren & Co., of same place.

Letters Patent No. 1512, dated Jan. 7, 1862.

The schedule referred to in these Letters Patent and making part of the same.

To all whom it may concern:

Be it known that I, David Hathaway, of the City of Troy, in the County of Rensselaer, and State of New York, have invented or produced a new and original ornamental Design for Plates of an Elevated Oven Cooking stove, and I do hereby declare that the following is a full and exact description of my said invention or production, reference being had to the annexed photographic drawings, in which -

Fig. 1 is a perspective view of the lower part,

Fig. 2 an elevation of the front plate of the elevated part,

Fig. 3 an elevation of the end plate and door of the elevated oven portion, all of a stove having my said ornamental design; each of the said photographs being on a different scale.

The distinguishing feature of my said ornamental design is the arrangement, upon each of the lower front doors A.A. Fig. 1. of the niche b, and projection c, surmounted and flanked by the combined semi-circular, rectangular, and pendent mouldings, d. d; the arrangement, upon the sides of the lower front plate E, Fig. 1. of the sunken panels f. f, each having the row of ornaments g, along its straight base, and the curved pendent moulding h, on its rounded upper part; the arrangement, upon the front plate, Fig. 2. of the elevated oven, of the niche i, furnished with the projecting base j, shell k, and arched pendant l, and surmounted and flanked by the main and lateral pendent supported arches q, and l. l, mouldings m. m. m, and panels n. n, all surrounded by the panel moulding p; and the arrangement, upon the end door R, Fig. 3. of the elevated oven, of the niche s, furnished with the projecting base t, shell u, and arched columnar moulding v, and surmounted and flanked by the arched columnar moulding w, and the compound, acanthine, and semi-circular mouldings x. y, and pendants z; the whole as shown by the annexed photographs.

What I claim as new and of my invention or production and desire to have secured by Letters Patent, is elevated oven cooking stove plates shaped and ornamented as herein described.
